CLAIM

USPC **D10/96**

I claim the ornamental design for a fluid flow meter, as shown and described.

(58) **Field of Classification Search**

DESCRIPTION

USPC D10/96
CPC G01F 1/40; G01F 1/42; G01F 1/44; G01F
1/46; G01F 1/74; G01F 11/003; G01F
11/006; G01N 21/03; G01N 21/05; G01N
2021/0378; G01N 2021/0382; G01N
2021/052; G01N 2021/054; G01N
2021/056; G01N 2021/058

See application file for complete search history.

(56) **References Cited**

FIG. 1 is a front perspective view of a fluid flow meter according to an embodiment.

U.S. PATENT DOCUMENTS

FIG. 2 is a rear perspective view of the fluid flow meter illustrated in FIG. 1.

FIG. 3 is a top plan view of the fluid flow meter illustrated in FIG. 1.

FIG. 4 is a front elevation view of the fluid flow meter illustrated in FIG. 1.

FIG. 5 is a rear elevation view of the fluid flow meter illustrated in FIG. 1.

FIG. 6 is a bottom plan view of the fluid flow meter illustrated in FIG. 1.

FIG. 7 is a left side view of the fluid flow meter illustrated in FIG. 1; and,

FIG. 8 is a right side view of the fluid flow meter illustrated in FIG. 1.

The dashed lines in various figures are for illustrative purposes only and form no part of the claimed design.
